UNITED STATES PATENT OFFICE.

ERASTUS B. BIGELOW, OF BOSTON, MASSACHUSETTS.

IMPROVEMENT IN BRUSSELS-CARPET LOOMS.

Specification forming part of Letters Patent No. 5,020, dated March 20, 1847; extended March 20, 1861; Reissue No. 1,523, dated August 18, 1863.

To all whom it may concern:

Be it known that I, ERASTUS B. BIGELOW, of Boston, in the county of Suffolk and State of Massachusetts, have invented certain new and useful Improvements in Power-Looms for Weaving Brussels Carpeting and other Wide-ile Fabrics; and I do hereby declare that the following is a full, clear, and exact description of the principle or character which distinguishes them from all other things before known, and of the manner of making, constructing, and using the same, reference being had to the accompanying drawings, making part of this specification, in which—

Figure 1 is a plan; Fig. 2, a front elevation; Fig. 3, an elevation of the left side, representing the jacquard-frame, as connected with the loom; and Fig. 4, a like elevation of the right side. The other figures will be referred to in their appropriate places.

The same letters indicate like parts in all the figures.

In the accompanying drawings, A A represent the two sides of a properly adapted frame connected by suitable cross-ties, B.

The lay, with its race-beam D, reed E, reed-bar F, and swords G G, but without shuttle-boxes, is made and operated as represented in the drawings, and in manner corresponding with that described in the Letters Patent granted to me on the 18th day of August, 1846, antedated 18th of February, 1846, for my "prol. loom for weaving ingrain carpeting, or these may be made in any other appropriate manner, as this makes no part of my present invention. The cams that operate the lay are on the cam-shaft I, on which there is a cogged wheel, M, that engages with another cogged wheel, N, on an intermediate shaft, O, that receives motion from a pinion, P, on the driving-shaft Q of this part of the machinery. On the intermediate shaft, O, there is a pinion, P, which drives by the cogged wheel n⁵ the shaft w⁵, to which it is attached, and on this shaft are the two picker-cams p¹⁰ q¹⁰, that alternately act on rollers u¹⁰ v¹⁰ on the ends of arms s¹⁰ l¹⁰ of a horizontal arbor, r¹⁰, to the other end of which is attached an arm, w¹⁰, for the purpose of operating the pickers w⁵ by means of the picker-staffs r⁵, connected with it by the straps y¹⁰ x¹⁰. This same shaft n⁵ carries two other cams, m⁵ and

s⁵, the one, s⁵, for the purpose of depressing a lever, l⁵, that turns on a fulcrum-pin, k⁵, on the lower cross bar, B, and this lever is connected at h⁵ by a rod, g⁵, with an arm, f⁵, on an upper horizontal shaft, d⁵, that has its bearings in the boxes e⁵ e⁵, from which project two other arms, e⁵ e⁵, and opposite to the one f⁵; and to these two arms are suspended the movable comber-board w⁵ by the two connecting rods b⁵ and the slide-rods x⁴ x⁴, that slide in bearings y⁴ y⁴ and z⁴ z⁴, the rods x⁴ x⁴ having shoulders to sustain the comber-board in its lowest position. The cam m⁵ is so formed as to depress the lever to elevate the comber-board for the purpose of elevating the figuring-warp at the required time, that the common harness may work the linen or foundation warp without interfering with the figuring-warp. This method of elevating the figuring-warp has been secured to me by Letters Patent No. 2,653, granted for improvements in the manner of mounting the loom, &c., and bearing date the 30th day of May, 1842, and antedated to run for fourteen years from the 1st of May, 1842, in the specification of which will be found a full, clear, and exact description of the nature and object of the invention and the mode of operation. There is another lever, l⁵, similar to and by the side of the lever l⁵ and operated by the cam m⁵, which is connected with and operates the jacquard. On the said intermediate shaft, O, there is another pinion, e¹⁰, which engages with a cog-wheel, n¹⁰, in a tubular arbor that runs on a stud projecting from the frame, and to this are attached the two harness-cams a¹⁰ and b¹⁰, that operate the harness y⁵ by the usual connection of levers c¹⁰ d¹⁰, connecting rods e¹⁰ g¹⁰, and second levers m¹⁰. The woven fabric is taken up after passing over the breast-beam C by passing between two rollers a⁵ b⁵, the upper one, a⁵, being used to make pressure on the other (to insure the drawing of the fabric) by means of two rods that pass through one of the cross-ties B, and provided with helical springs d⁵ d⁵, and the lower one, b⁵, receives the regular take-up motion to insure the regularity of the figures, the apparatus which gives this motion consisting of a cogged-wheel, x⁵, in the roller b⁵, which engages with a pinion, g⁵, or the arbor of a ratchet-wheel, f⁵, operated at each beat of the lay by a hand, k⁵, on the end of lever, l⁵,

connected with one sword of the lay at p^9 by a jointed connecting-rod, a pawl, n^9 , being employed to prevent the ratchet-wheel from turning back. The linen or foundation warp $w^3 x^3$ is given out from the warp-beam a^3 by a connecting-rod, o^9 , one end of which is jointed to the sword of the lay at the same point, p^9 , to which the take-up motion is connected, the other end being jointed to one end of a lever, u^9 , that turns freely (as represented by dotted lines in Fig. 3) on a vertical arbor, s^3 , which has a crown ratchet-wheel, t^9 , actuated at each beat of the lay by a hand, v^9 , on the opposite end of the lever u^9 . As this ratchet-wheel and arbor are turned, motion is given to the warp-beam by an endless screw, r^9 , on the upper end of the arbor, the threads of which take into the cogs of a spur-wheel, q^9 , on the shaft of the warp-beam.

For the purpose of regulating the let-off motion the foundation-warps from the warp-beam pass over a whip-roller, b^4 , that has its bearings in the upper end of two levers $c^4 d^4$, that vibrate on centers e^4 , and the lower end of each of these levers is provided with a segment rack, f^4 , the teeth of which engage with pinions g^4 on each end of a shaft, h^4 , and on this shaft there is a cam, z^4 , against the periphery of which one arm (represented by dotted lines in Fig. 3) of a lever, u^9 , that turns on a stud-pin, x^9 , bears, the other arm of this lever being connected with the ratchet-hands v^9 by a chain, y^9 , and the diameter of this cam is such that so long as the end of the lever u^9 bears on its greatest diameter, the ratchet-hand is held up and does not act on the ratchet-wheel to turn the warp-beam and give out the warp, but so soon as the tension of the warps becomes great on the roller b^4 as to overcome the force of a weight, n^4 , attached to one end of a strap, l^4 , that passes over a roller, m^4 , and is attached to and extends partly around the periphery of a brake-wheel, o^4 , on the before mentioned shaft h^4 ; this shaft is turned and brings the reduced diameter of the cam to the arm of the lever, which permits the ratchet-hand to act on the ratchet-wheel and give out the warp, so that the giving out of the warp is entirely regulated by its tension on the roller b^4 , over which it passes.

This mode of giving the warp I do not claim, as it is the subject of previous Letters Patent granted to me.

To prevent the lay when beating up the weft from causing the warp-beam to give out warp, there is a brake, p^4 , fitted to the periphery of the brake-wheel o^4 , with one end jointed at q^4 to the frame, and the other by a connecting-rod, r^4 , to the sword G of the lay, so that as the lay beats up the brake is drawn up to the brake-wheel and holds fast the let-off motion.

I have thus far described the general organization of that part of the mechanism which is employed in forming the foundation and weaving in the fabric, but in the arrangement the parts are so located generally on

one side as to leave free space for the location and operation of the second part of the mechanism, or that which is employed in operating the figuring wires.

The shuttle-boxes $K K$, instead of being attached to and making part of the lay, are permanently attached to the sides of the frame by means of the plates $I I$, the ends of the race-board of the lay being properly adapted to pass under them when the lay is thrown back so that the shuttle can pass over the race-board back and forth from one shuttlebox to the other.

Before proceeding to the description of the second part of the mechanism I will simply state the jacquard-frame s^4 is applied in the usual manner and so located as to have the cords t^4 , &c., (through the mails of which the figuring-warps pass) in front of the harness $y^3 z^3$, that works the linen or foundation warps. These cords pass through holes in the movable comber-board, and are provided each with a knot, q^6 , so that by lifting the comber-board all the figuring-warps are lifted up clear of the foundation-warps to admit of working these without interruption from the figuring-warps.

At the commencement of each operation the first part of the mechanism is set in motion to weave the foundation-web in the usual manner of weaving ordinary cloth, which, therefore, needs no further description than that given above, as this part of the mechanism makes no part of my present invention, except so far as I have given it an organization and arrangement which adapts it to the second part of the mechanism, so that the two shall work in succession.

During the first series of operations the comber-board u^4 is lifted by the cam s^5 to raise the jacquard-harness, and in like manner the jacquard is operated by the cam u^5 to raise that portion of the figuring-warp which is to form the figuring loops or pile at the next operation, these two operations being performed by the first part of the mechanism; and at end of the weaving in operations and before the first part of the mechanism is arrested, the comber-board is permitted to descend to let down that portion of the figuring-warp which is not to form the surface, and so soon as this is effected the first part of the mechanism is arrested and the second part started by the following arrangement, more particularly represented in Figs. 14, 15, 16, and 17, late 6.

On the shaft n^5 of the jacquard and comber-board cams there is a cam-formed arm, c^6 , which gradually lifts an arm, b^6 , (projecting from an arbor, a^6 ,) and which then, by its form, permits it to fall back to its original position by the force of a weight, f^6 , on another arm or lever, d^6 , on the same arbor. The end of this weighted lever is hook formed, and in descending catches onto a pendent hook, l^6 , (Fig. 4,) jointed at m^6 to a vertically sliding rack h^6 , provided with cogs on two of its faces, those on one face engaging with a cogged wheel, u^6 , that turns on

the stud-pin o^6 , and those on the other face engaging the cogs of a sector-rack, t^6 , that turns on a stud-pin, v^6 . As the lever d^6 draws down the rack h^6 , it turns the cogged wheel n^6 , on the arbor of which there is a pinion, p^6 , that engages with a sector-rack, q^6 , that vibrates on the stud-pin r^6 , and to this is attached a belt-shifter, s^6 , so that the descent of this rack shifts the driving-belt s from the pulley R on the driving-shaft Q of the first part of the mechanism, and transfers it to the driving-pulley U of the driving-shaft V of the second part of the mechanism, which is thus started as the first part is arrested. As the driving-belt is shifted from one driving-pulley to the other, it passes over a loose pulley, T , to prevent strain on the mechanism; and at the same time it is necessary to arrest the momentum of the machinery from which the driving-power has been removed. This is effected by the sector-rack t^6 , to the hub of which there is a short arm, a^6 , connected by means of an adjustable connecting-rod, y^6 , with a brake, z^6 , which is thus forced against the inner periphery of the driving-pulley to arrest by friction all the moving parts.

On inspection of the drawings it will be seen that there is a like arrangement of parts on the other side for the purpose of shifting the driving-belt back from the second to the first part of the mechanism, in which y^5 is the cam-formed arm that acts on the arm z^5 of the arbor a^5 , from which projects the weighted lever e^5 , that catches on the pendent hook to draw down the double rack t^5 to vibrate the cogged wheel n^5 and sector-rack v^5 , that operates the brake u^5 within the pulley R by the connecting-rod y^5 . As the levers d^6 and e^5 move together, and alternately act on the pendent hooks, that one of the sliding double racks may be lifted as the other is drawn down. Provision is made alternately to place the pendent hooks out of the way, which is effected in the following manner, viz: As the pendent hook is drawn down by the lever d^6 , a pin (represented by dotted lines in Fig. 17) that projects from the pendent hook runs within the flanges of a plate, $d^7 b^7 c^7$, and in front of a spring, e^7 , attached to the plate by screws $f^7 g^7 h^7$, and at the end of the downward motion forces back the spring and gets behind it, so that when the lever d^6 is moved down at the next operation by the lever e^5 , which operation carries up the pendent hook, it (the hook) is carried back to avoid catching the end of the lever by the curved form of the spring, and so soon as it passes above the top of the spring it is forced forward to catch the end of the lever at the next operation by a spring, v^7 , attached to the rack.

The first part of the mechanism having been stopped, and the figuring warps placed in a condition to receive the wires over which the figuring-loops are to be formed, and the driving-belt shifted to the pulley U on the driving-shaft V of the second part of the mechanism, the second series of operations

commence, which are for introducing a wire under that portion of the figuring-warp which is to be formed into loops, at the same time drawing out a wire from under the wrought figure, and then supporting and transferring this wire toward the point where it is to be reinserted in the open shed of the figuring-warps at the next operation.

The details of the arrangement of the apparatus for operating the figuring-wires are more closely represented on Plate 5, Fig. 5 being a vertical cross-section taken in front of the lay, looking from the back; Fig. 6, a vertical section taken in the direction of the warps; Fig. 7, a section taken through and in the length of the pinchers; Fig. 8, a horizontal section taken just above the lay; Fig. 9, a vertical section taken through the arbors of the fingers for transferring the figuring-wires; Fig. 10, a separate view of the box for introducing the figuring-wire to show its connection with the carriage to which it is attached; and Figs. 11, 12, and 13, separate sections of the box for introducing the figuring-wires to exhibit the arrangement of the parts for dropping them.

On the end of the driving-shaft V there is a miter-wheel, W , that engages with a similar wheel, X , on one end of a shaft, Y , that turns in collars $Z Z$ of the frame a , that is attached to and turns freely on the driving-shaft V to admit of the vibration of the shaft Y , independently of the motion of the driving-shaft, in the usual manner of making a mangle-wheel motion, the other end of the shaft being free to turn and slide in a groove, e , in a bracket, d , attached to the side of the frame, and to the extremity of this shaft is attached the mangle-pinion b , which acts on the external mangle-rack c to give a reciprocating rectilinear movement to a main carriage, f , and all the parts attached to it, the said carriage sliding between ways g g' , projecting from a plate, h , attached to the frame just below the breast-beam c and projecting sufficiently beyond the frame on the right to admit of carrying the main carriage f , and the parts attached to it out of the way during the operation of weaving. The mangle-rack at the ends is for a short distance straight and vertical instead of being semicircular as usual, that all the mechanism which is carried by it may remain in a state of rest for a short time at the end of each motion, while the mangle-pinion is carried up or down. From the carriage f projects an arm, h^3 , having a slot, g^3 , in which slides a bolt, c^3 , projecting from a secondary carriage, b^3 , that slides in ways e^3 e^3 in a plate, d^3 , attached to the front of the lay, so that by this connection the secondary carriage can move with the lay, and when the main carriage is moved by the mangle motion this secondary-carriage is also carried with it. To the right-hand end of this secondary carriage is attached at a^2 a long box, z^2 , with one end made in the form of a shuttle to admit of its free passage between the warps, the said box

having a hopper-like opening, i^3 , at the bottom of sufficient length and width to receive and discharge through the bottom thereof a figuring-wire; but within the hopper, at equal distances apart, there are three curved arms, p^3 , (two only are shown in the drawings,) projecting from an arbor, s^3 , that runs the whole length of the box and having its bearings in the ends thereof, one end of the said arbor being provided with another arm, m^3 , jointed to an arm, o^3 , of a short vertical arbor, p^1 , surrounded by a helical spring, q^3 , and provided with an arm, r^3 , at the upper end. The tension of the helical spring always tends to turn the arbor which it surrounds, to keep, by the described connections, the curved arms p^3 up, so as to support the figuring-wire; but when the arm r^3 of the vertical arbor is brought into contact with a projection, s^3 , on the bar F of the lay when the box z^2 is carried under the figuring-warp, as represented by dotted lines in Fig. 8, the curved arms are thrown open and the figuring-wire dropped, the arms being closed by the tension of the helical spring so soon as the box is withdrawn from the open shed by the mangle motion.

The carriage f , which is described above, communicates motion to the box that carries the figuring-wires, and also carries the pair of pinchers that withdraws the wires z from under the figuring-loops. A standard, i , projects upward from this carriage, to the upper end of which, at m and n , are jointed the two jaws k l , that constitute the pinchers, the two being provided with segment-cogs o p , to insure their opening and closing together. The lower jaw, l , has an arm, l' , which, when the jaws are closed, is held under a catch, d , r , on the end of an arbor, S , carried by a standard of the carriage f , and around this arbor is a helical spring, t , which bears the catch toward the arms l' of the jaws, there being an arm, v , in the same arbor, the end of which runs on the upper edge of the plate h . When the carriage is started by the mangle-pinion at the commencement of the second series of operations, the jaws are open, and are carried toward the right-hand selvage of the fabric as the box with the figuring-wires moves under the figuring-warp, and when these approach the end of this motion that wire z which is to be drawn out from under the formed loops must be pushed partly out and toward the open pinchers. This is effected by a mechanism attached to an arm, e' , that vibrates on an axle, g' , in box's f' , f'' , attached to the front tie piece, B , of the frame. At the upper end of this arm there is a plate, n' , which is borne (by a spring of any kind or a weight that acts on the arm) against the first which is to be withdrawn of a series of wires, z , several being retained under the figuring-loops to prevent the tension of the warps and the operation of the loom from drawing out the formed loops. A wedge-formed instrument, h' , that slides in brackets i i' , attached to the arm e' , is then forced up between

the wire that is to be drawn out and the one next to it by a cam, k' , that turns on a stud-pin, l' , on the arm, and the cam is vibrated to force up the wedge by a cam, x' , on a shaft, y' , that receives motion from the driving-shaft V by a train of wheels and pinions, u^5 v^5 u^5 x^5 , the proportions of this train being such as to give the shaft y' one revolution for the complete series of motions performed by the second part of the mechanism. The cam is so formed and situated on its shaft as to elevate the wedge at the proper time by acting on a lever, r' , that turns on a fulcrum-pin, w' , and acts on a bent lever, w' s' , that turns on a fulcrum-pin, t' , the said lever being connected by a rod, r' , with the cam k' . So soon as the wedge is forced up the surface of the cam k' is then concentric, to admit of its further vibration without moving the wedge, the object of giving a further vibration to the cam k' being to move a lever, m' , that vibrates on a stud-pin, o' , on the same arm, to force the wire z toward the pinchers—that face of the lever which acts on the point of the wire being grooved for this purpose. The cam k' acts on the lever to vibrate it to and fro by means of two pins, p' q' , (shown in Fig. 5 by dotted lines,) the pins being placed so far apart as to admit of the vibration of the cam k' sufficiently far to elevate the wedge before it acts on the pushing-lever, as one motion should follow the other.

The operations just described, which separate and push out the figuring-wires, take place as the pinchers move toward the wire, and when the wire is introduced between the jaws of the pinchers they are closed by forcing down the arm l' of the under jaw until caught and held by the catch d' , which is effected by a lever, w , that turns on a stud-pin, y , on a standard, x , this lever being connected by a jointed rod, b' , with one end of a lever, s' , that vibrates on a stud-pin, w' t' , the other end of this lever being acted upon at the appropriate time to close the pinchers by a cam, u^4 , on the shaft y' . The moment that the pinchers have grasped the wire, which takes place at the same time that a similar wire is dropped from the box under the figuring-warp, the mangle-pinion during the operation of grasping the wire passes up that portion of the end of the mangle-rack which is straight and vertical, and which therefore does not move the carriage that carries the pinchers and wire box; but so soon as the wire is grasped the mangle-pinion begins to move back the carriage, and at the end of the back-motion the arm v of the latch of the pinchers is carried up an inclined plane, u , on this plate, which forces back the latch d' , and permits the spring q to force open the jaw and liberate the wire, which falls into the supporting and transferring apparatus, which will now be described. There is a sliding standard, e^2 , which slides vertically in brackets f^2 f^2 , attached to the sides of the frame, and to the top of this standard is attached a horizontal top piece, d^2 , with the ends c^2 c^2 bent down to receive the journals of two small ar-

bors, $b^2 n^2$, to which are attached near each end curved fingers $a^2 a^2$ and $z^2 z^2$, two at each end, their hubs being provided with cogs o^2 , that engage each other, so that by turning one of the arbors by an arm, p^2 , attached to it, the two pairs of fingers can be made to open and close. The outer end of the arm p^2 is connected by a jointed rod, q^2 , with one end of a lever, r^2 , that vibrates on a stud-pin, r^2 , the other being provided with a roller, S^2 , to receive and communicate motion to the parts in connection, from a cam, t^2 , on the shaft y^2 , and attached to the face of another cam, m^2 , which acts upon a roller, k^2 , on the end of another and similar lever, h^2 , on the same stud-pin, the other being provided with a roller, g^2 , on which the lower end of the standard e^2 rests, and by which it is elevated and permitted to descend. To the lever h^2 there is jointed a pendent catch, $v^2 w^2$, which catches on to a projection, x^2 , on the other lever r^2 , for the purpose of connecting and disconnecting the two wires, at given periods in the operation of the mechanism. During the operation of introducing and withdrawing the wires the two levers are disconnected, and the standard e^2 is kept at the highest position by the rollers on the lever that operates it, being acted upon by that part of the cam-wheel m^2 which is concentric, and the fingers are kept open by the preponderance of the parts on that end of the lever r^2 connected with the fingers. The parts being thus situated, as the pinchers approach their drawing-out movement, the standard, with the fingers $e^2 n^2$, begins to descend by the rotation of the cam m^2 , the depression w^2 , in which passes the roller k^2 , and permits that end of the lever h^2 to rise by the weight of the standard, &c., resting on the other end, and as the standard descends the points of the opened fingers pass below the wire in the pinchers, and then the cam t^2 acts on the roller of the lever r^2 and closes the fingers under the wire, which is dropped into them by the opening of the pinchers, and the wire is there held by connecting the two levers together by the catch $v^2 w^2$. The parts remain in this situation until the driving-belt is shifted back from the driving-pulley U of the second part of the mechanism to the driving-pulley R of the first part, which is effected as described above. This sets in motion the weaving-in operation, and the first beat of the lay brings the box which conveys the wire under the figuring-warp under the fingers, and at the same time a projection, y^2 , on the sword G of the lay liberates the catch $v^2 w^2$ and permits the lever r^2 to descend and open the fingers to drop the wire into the box preparatory to the next operation of introducing the wire under the figuring-warp. After the driving power has been shifted back, the weaving-in or first part of the mechanism the jackguard-frame is operated by the cam m^2 and its connections to let down the figuring-warps that were thrown up to form the figuring-loops that they may be woven in, and when the lay has made one beat

for this purpose the comber-board is elevated to lift the figuring-warps out of the way of the operation of the linen or foundation warps, as above described.

From the foregoing it will be obvious that the parts of this mechanism which I claim as my invention can undergo many modifications without changing the principle of my invention—as, for instance, instead of using the mechanism above described for shifting the belt from one driving-pulley to the other, a clutch may be substituted, or any other arrangement of mechanical means which will shift the belt from one to the other or clutch and unclutch the parts, the object being to start one part of the mechanism as the other is arrested, a brake being used for each separate organization, so that the moment the driving-power is shifted the brake shall act to arrest the momentum of the moving parts. Again, instead of using fingers that open and close to receive and deliver the figuring-wires, hooked arms may be employed and connected with an arbor, so that they can turn to pass under the wire to receive it from the pinchers, and in like manner turn to drop it into the box which carries it under the figuring-warps; and, instead of the hopper and shuttle formed box for receiving, holding, and introducing the wires, arms such as are employed in the box to close and open the bottom for the delivery of the wire may be used without the box by giving them a greater curve, as the main object is to give the wire ample support as it passes between the warps. It is obvious that the principle of my invention may be applied in various modes other than that which is contained in the description herein or those which have been just suggested as practicable, the substantial and characteristic operations of my loom admitting of much variety in the particular mechanical devices by which they are performed. It will also be obvious that any of the parts of my invention above described may be employed without the others by performing the other required operations by other means—as, for instance, that part of my invention which operates the two parts of the machinery by a separate organization of mechanism, so combined together that the driving-power can be shifted from the one to the other, can be beneficially employed without reference to the mode of removing the figuring-wires from the woven pile, of supporting and transferring them to the box or trough for their reception, and of supporting them between the open figuring-warps, for however these operations or functions are effected, whether by machinery or by hand, all the advantages due to the first part of my invention will be attained; and in like manner the substantial means here provided for operating the pile-wires may be advantageously used in a loom, the weaving mechanism of which is not organized separately from and combined with the mechanism for operating the pile-wires.

Each of the several operations to which the

pile-wires are subjected, such as supporting, transferring, holding in position, and reinserting, may be performed to advantage by the use of the substantial means here provided for such operation, though the other operations be performed by means substantially different from those here provided therefor; but I believe the best results will be attained by using as a whole the means of automatically operating the pile-wires in the manner substantially as hereinbefore described.

What I claim as my invention, and desire to secure by Letters Patent, is—

1. The organized means of operating the pile-wires automatically, whereby they are successively withdrawn, supported, transferred, and inserted, substantially as described.

2. The employment of fingers, or the equivalent thereof, as means of transferring the pile-wires toward their desired position for insertion into the shed of the figuring-warps, substantially as described.

3. The method of introducing the pile-wires into the shed of the figuring-warps by means of a trough, or the equivalent thereof, which supports and carries them into the shed, drops them therein, and then moves back for the succeeding wire, substantially as described.

4. The above-described means of supporting

the pile-wires while being transferred toward their desired position prior to and for insertion into the shed of the figuring-warps.

5. The above-described means of supporting the pile-wires in position ready for insertion into the shed of the figuring-warps, and all equivalent means for effecting the same end, when said means form a part of an organized method of wholly operating the pile-wires automatically.

6. The above-described (and all equivalent) means of supporting the pile-wires while being inserted into the shed of the figuring-warps, when said means form a part of an organized method of wholly operating the pile-wires automatically.

7. Making the mechanism which weaves or forms the body of the cloth separate and with a distinct organization from the mechanism which operates the pile-wires, each mechanism being operated separately, and the two being connected by an intermediate mechanism which starts one of them as it arrests the other by shifting what communicates the motive power from the one to the other.

E. B. BIGELOW.
